United States Patent

Des. 235,356
Patented June 10, 1975

235,356

CHEMICAL VAPOR DEPOSITION REACTOR OR SIMILAR ARTICLE

William George Faraco, Jr., 13561 Howen Drive,
Saratoga, Calif. 95070

Filed Nov. 1, 1973, Ser. No. 411,728

Term of patent 14 years

Int. Cl. D15—09

U.S. Cl. D32—2

FIG. 1

FIG. 2

FIG. 3

FIG. 4

FIG. 1 is a front elevational view of the chemical vapor deposition reactor embodying my new design.

FIG. 2 is a side elevational view of one side thereof.

FIG. 3 is a rear elevational view thereof.

FIG. 4 is a side elevational view of the opposite side thereof.

The undisclosed top and bottom of the chemical vapor deposition reactor are plain and unornamented.

I claim:

The ornamental design for a chemical vapor deposition reactor or similar article, substantially as shown and described.
